UNITED STATES PATENT OFFICE.

VIRGINIA I. COPLAND, OF WASHINGTON, DISTRICT OF COLUMBIA.

ERASING-SHIELD.

SPECIFICATION forming part of Letters Patent No. 680,227, dated August 13, 1901.

Application filed June 8, 1901. Serial No. 63,731. (No model.)

To all whom it may concern:

Be it known that I, VIRGINIA I. COPLAND, a citizen of the United States, residing at Washington, in the District of Columbia, 5 have made certain new and useful Improvements in Erasing-Shields, of which the following is a specification.

My invention is an erasing-shield for use on type-writers, and is especially designed 10 for use on work which is being manifoldeled by carbon-sheets, and has for an object to provide in connection with the section for protecting the impressions adjacent to that being erased a base for the pressure of the 15 eraser, so the act of erasing will not cause the carbons to blur the carbon copy or copies.

The invention consists in certain novel constructions and combination of parts, as will be hereinafter described and claimed.

20 In the drawings, Figure 1 is a perspective view of my invention as in use. Fig. 2 is a detail perspective view of the device inverted to show the base-section. Fig. 3 is a cross-section on about line 3 3 of Fig. 1, and Fig. 4 25 shows a shield in which the two sections of the shield are folded from a single strip.

In erasing from a sheet on the platen of a type-writer difficulty is experienced when carbon-copies are being made because the 30 carbon-copies will be blurred or blotted by the carbon-sheets under the pressure of the eraser. My invention aims to overcome this by providing in connection with the perforated shield-section an underlying base-section, which in practice will overlie the carbon- 35 copy and receive the pressure of the eraser.

The shield is shown as composed of the perforated section or sheet A, having perforations A', through which the eraser may operate, and the base-section B, connected at one 40 end with the section A and free at other points therefrom, so it can be slipped under the type-copy being made and rest thereunder over the carbon-copy. The openings A' in the 45 section A are suitably arranged to permit the rubber to reach through to the letter or word to be erased and at the same time protect the adjacent letters from the action of the rubber.

The shield may be made of any suitable flexible sheet material, and I find that thin 50 sheet-celluloid gives good results, being flexible enough to bend longitudinally and transversely to conform to the platen.

In Fig. 4 the shield is represented as formed in a single piece, while in Fig. 2 the guard-section and base-section are separate and are secured together at one end by suitable fastenings, shown as small riveted eyelets C.

The device is simple, can be cheaply made, is easily adjusted for use, and will be found 60 efficient for the purpose for which it is designed, as above described.

Having thus described my invention, what I claim, and desire to secure by Letters Patent, is—

1. An erasing-shield composed of the upper section perforated to permit the operation of the eraser through it and the base-section in connection therewith and adapted to fit between the type-copy and carbon-copy and 70 overlie the latter, substantially as set forth.

2. An erasing-shield composed of the section having openings through which the eraser can operate and the base-section connected at one end with the upper section and adapted to 75 underlie the type-copy and receive the pressure of the eraser, substantially as set forth.

3. An erasing-shield consisting of the upper or main section or strip perforated to permit the operation of the eraser through it, the 80 base section or strip and the riveted eyelets connecting said strips at one end, substantially as set forth.

4. The erasing-shield herein described composed of two flexible strips one of which is 85 provided with openings through which the eraser may operate and the other of which is imperforate and is adapted to underlie the sheet being erased and is closed or imperforate opposite the openings in the first plate, 90 and the fastenings connecting said strips at one end, substantially as set forth.

VIRGINIA I. COPLAND.
